PHOTOGRAPHIC FLASH GUN

Frank James Rizzatti, Brooklyn, N. Y., assignor
to Burleigh Brooks Co., New York, N. Y., a part-
nership

Application August 25, 1950, Serial No. 11,929

Term of patent 14 years

(Cl. D61—1)

To all whom it may concern:

Be it known that I, Frank James Rizzatti, a citizen of the United States of America and resident of Brooklyn, in the county of Kings and State of New York, have invented a new, original, and ornamental Design for a Photographic Flash Gun, of which the following is a specification, reference being had to the accompanying drawings, forming part hereof:

Fig. 1 is a side elevational view of a photographic flash gun, showing the new design;

Fig. 2 is a rear elevational view thereof; and

Fig. 3 is a front elevational view of the lower portion only thereof.

The characteristic features of the design reside in the portions shown in full lines.

What is claimed is:

The ornamental design for a photographic flash gun, substantially as shown and described.

FRANK JAMES RIZZATTI.
